TIE WIRE TIGHTENING AND TWISTING DEVICE

Filed May 13, 1929

UNITED STATES PATENT OFFICE

LELAND M. VAN SLYKE, OF NORTH HOLLYWOOD, CALIFORNIA

TIE-WIRE TIGHTENING AND TWISTING DEVICE

Application filed May 13, 1929. Serial No. 362,643.

My invention relates to a device for tightening and twisting tie wires on forms for making concrete walls and the like.

The objects of my invention are: First, to provide a device of this class whereby the wires used for tying the opposite sides of forms together may be easily, quickly and efficiently tightened and twisted so that the opposites of the form may be rigidly held in position; second, to provide simple and economical means for drawing the wires tightly through the form and whereby great leverage may be had with the device so that the wires may be drawn taut with little effort; third, to provide a device of this class whereby the two ends of a wire may be gripped simultaneously and held tightly while the ends are twisted, and also to provide means in connection therewith whereby the wires may be intermittently drawn taut while the ends are being twisted; fourth, to provide a device of this class for cutting off the extended ends of the wire, and also a device whereby the extended ends of the wires may be cut off during substantially the same operation of gripping the free ends thereof; fifth, to provide a device of this class which will leave the ends of the wires, after the same are twisted, in such position that working men will not be readily injured thereby; sixth, to provide a device of this class in which the means used for effecting the cutting operation and drawing together the gripping jaws is also used for rotating the gripping jaws for twisting the wires; seventh, to provide a device of this class whereby the cutting and gripping jaws or members may be readily renewed when desired; eighth, to provide as a whole a novelly constructed device for tightening and twisting tie wires; and, ninth, to provide a device of this class which as a whole is simple and economical of construction and operation, which is durable, and which will not readily deteriorate or get out of order.

With these and other objects in view, as will appear hereinafter, my invention consists of certain novel features of construction, combination and arrangement of parts and portions as will be hereinafter described.

in detail and particularly set forth in the appended claims, reference being had to the accompanying drawings and to the characters of reference thereon which form a part of this application in which:

Figure 1 is a side view of my tie wire tightening and twisting device in one form of construction, Fig. 1 being designated for the purpose herein as a top side view; Fig. 2 is a partial side and partial sectional view thereof taken at 2-2 of Fig. 1, certain parts and portions being shown in elevation to facilitate the illustration; Fig. 3 is a fragmentary sectional view thereof taken at 3-3 of Fig. 2, showing the free ends of a wire positioned between the jaws thereof; Fig. 4 is a sectional view thereof taken at 4-4 of Fig. 2, showing the inner side of the outer jaw and cutting member; Fig. 5 is a sectional view thereof taken through 5-5 of Fig. 2; and, Fig. 6 is a plan view on a small scale of a fragmentary portion of a form for making concrete walls, showing by dotted lines my device in operative position for drawing one of the wires taut prior to twisting the same.

Like characters of reference refer to similar parts and portions throughout the views of the drawings.

My tie wire tightening and twisting device is primarily mounted on and partially enclosed in a hollow handle 1 which is preferably a tubular member of convenient size to handle. At one end of the handle 1 is provided an arm 2 which is offset with respect to the axis of the handle 1 and extends beyond the end thereof a considerable distance. This arm forms a pivot member about the end of which the handle 1 and its associated parts are tilted. This arm or pivot member may be integrally secured to the end of the handle or the same may be a separate removable member encircling said end of the handle 1 and secured thereto by a screw 3 or other suitable means. On the back side of the arm or pivot member and at a considerable distance from the end thereof is provided a claw 2a into which the end of a wire may be bent for gripping the wire and for tightening the same when the end of the pivot member is

fulcrumed on a member of the form through or adjacent which the wire extends, as will be more specifically described hereafter.

In the hollow handle or tube 1 is positioned and rotatably mounted a smaller tube 4 which is preferably of the same length or very slightly longer than the tube 1. To the one end of the tube 4, coincident with the end of the tube 1 to which the pivot member is secured, is secured a jaw 5, which may be integrally secured thereto or which may consist of a separate member, as shown in Figs. 2 and 3. As shown in the drawings, the jaw member is provided with a sleeve 5a which is positioned within the tube 4 and is prevented from removal therefrom by a screw 6 which is secured to the sleeve 5a and extends with its head into a hole in the side wall of the tube 4. The sleeve 5a is also preferably keyed to the sleeve 4 by longitudinal keys 5b at the exterior surface of the sleeve, which keys extend into slots 4a in the side wall of the tube 4, as shown best in Fig. 5. The jaw 5 extends transversely of the axis of the tube 4 and is provided at its outer side with longitudinal grooves and ridges 5c.

Through the axial portion of the jaw 5 is extended and reciprocally mounted a square shank 7 which extends partially into the tube 4 and also beyond the outer side of the jaw 5. To the extended end of the shank 7 is secured the movable jaw 8 which also extends transversely of the axis of the shank 7 and is positioned in opposed relation to the jaw 5. The jaw 8 is preferably removably secured to the end of the square shank 7 by a nut 9. The two ends of a single tie wire are adapted to be clamped between these two jaws with the end of the tie wire at the opposite side of the square shank, as shown best in Fig. 2.

Both of the jaws also serve as cutting members for cutting off the extended ends of the wire. For this purpose there is provided on one of the cutting members, preferably on the movable member 8, a pair of cutting edges 8a which are extended inwardly at the opposite sides and opposite ends of the member 8 and are adapted to be shifted past the outer face 50 of the jaw 5 at the opposite lateral sides thereof, thus forming substantially two pairs of shears at the opposite sides and end of the jaw members when the same are shifted together, as shown by dotted lines in Fig. 3. It will be noted that one of the cutting edges of the member 8 is positioned at one side thereof and is adapted to cut the end of the wire positioned at one side of the shank 7, while the other cutting edge is positioned at the opposite side of the member 8 and is adapted to cut the end of the wire positioned at the opposite side of the shank 7. When the ends of the wires are cut, as stated, the jaws are adapted to be drawn tightly together, tightly clamping the cut ends of the

wire. At the opposite sides of the movable jaw 8 are also provided transverse grooves 8b into which the wires are adapted to be positioned when drawing the wire taut and when twisting the same, as shown in Figs. 2, 3 and 4, the wires shown in Fig. 3, and designated A therein, being shown with their ends only partly positioned between the jaws. To the opposite end of the inner tube 4 is secured a yoke 10 which is here also shown as provided with a securing sleeve 10a which may be secured to the tube 4 in a manner similar to the securing of the jaw 5 to the tube 4. The outer end of the yoke is bifurcated. Between the furcations 10b of this yoke is positioned one end of the cam lever 11. This cam lever is also bifurcated. Between the furcations 11a of this cam lever is positioned the eye 12a of the operating rod 12. Through the furcations of the yoke 10, the furcations of the cam lever 11 and through the eye 12a, is extended a guide and pivot pin or bolt 13. In the furcations 10a are provided longitudinal slots 10c which permit the bolts to slide longitudinally with respect to the yoke or the tubes 1 and 4. The edges of the furcations of the cam lever 11 are provided with cam surfaces 11b which are adapted to engage the furcations when the lever is shifted from its solid line position to the dotted line position, designated X and Y. The operating rod 12 is reciprocally mounted in the sleeve 10a and is secured at its inner end to the inner end of the shank 7. Intermediate the ends of the operating rod 12 is provided a shoulder 12b between which and the inner end of the sleeve 10a is positioned a compression spring 14 which spring is positioned around the operating rod. This spring is adapted normally to open the jaws when the lever 11 is in the solid line position. When the lever is shifted to the dotted line position, designated X, the movable jaw 8 is shifted to the dotted line position shown in Fig. 3, during which shifting of the lever, the ends of the wires are lightly gripped by the cutting edges. When the lever is then shifted to the dotted line position, designated Y, the jaws are drawn tightly together, cutting the wires and clamping and gripping the ends of the wire between the ridges 5c at the outer side of the jaw 5 and the inner side of the jaw 8. The cam surfaces are so arranged that the lever will remain in the dotted line position, designated Y.

When the wires are so clamped and the lever is in the last mentioned position, the jaws may be rotated about the longitudinal axis of the handle 1 by rotating the lever 11 about such axis. When the jaws are so rotated, the handle and pivot members are held stationary, which permits the pivot member to serve as a fulcrum for drawing the wires taut while twisting the same.

In Fig. 6 I have shown fragmentarily a form for making concrete walls. In this

view, the sheathing of the form are designated B, the usual vertical studs, to which the sheathing is secured, being designated C. To the outer sides of the studs are secured 5 whalers, designated D, which are positioned parallel to the boards B. A common custom of passing the tie wires through the forms is to pass the looped end A1 of the wires A around the whaler at one side, then passing 10 the wires either between the joints of the board B or through holes therein, then positioning the ends of the wires at the opposite sides of the whaler D at the opposite side of the form, then twisting the outer ends thereof 15 together, then twisting the two strands of the wire between the boards B until the same are taut. My method of tightening and twisting the wires and the application of my device is as follows:

20 After the wire is positioned through the form as stated with the ends thereof at the opposite sides of the last mentioned whaler, I place the end of the pivot member of my device against the outer side of the whaler at 25 an angle thereto and then bend one of the wires into the claw. I then tilt my device to a substantial perpendicular position to the whaler, which tightens the wire in the form. I then tighten the other end of the wire in 30 the same manner. I then bend or twist the previously bent end of the wire in opposite directions, as indicated by A2 and A3 in Fig. 6. I then place these ends between the jaws with the straight portions in the grooves 35 8b. 25 I then rotate the lever to the dotted line position X which grips the ends of the wire. I then shift the lever to the dotted line position Y which cuts off and securely grips the ends of the wires. I then place the pivot member 40 against the whaler and rotate the lever 11, intermittently and preferably at the same time tilting the device back and forth so as to intermittently draw the wires taut by the greater lever action of the device about its 45 fulcrum. The wires are then released.

By this method the wires may be quickly tightened without getting into inconvenient places between or within the form. With this device the wires may also be tightened 50 conveniently in portions of the form heretofore unaccessible by reason of beams, timbers, or floor forming forms at the upper end of the wall form.

Though I have shown and described a particular construction, combination and arrangement of parts and portions, I do not wish to be limited to this particular construction, combination and arrangement, but desire to include in the scope of my invention 55 the construction, combination and arrangement substantially as set forth in the appended claims.

Having thus described my invention, what I claim as new and desire to secure by Letters 60 Patent is:

1. In a device of the class described, a long handle, a pivot member extending beyond the end of the handle and positioned in offset relation to its axis and provided at its outer side with a claw, and a pair of jaws at said end of the handle at one side of the pivot member at the offset portion thereof. 70

2. In a device of the class described, a long handle, a pivot member extending beyond the end of the handle and positioned to one side of its axis and provided at its outer side with a claw, and a pair of jaws at said end of the handle at one side of the pivot member, said jaws being rotatable with respect to the handle. 75

3. In a device of the class described, a long handle, a pivot member extending beyond the end of the handle and positioned to one side of its axis and provided at its outer side with a claw, and a pair of jaws at said end of the handle at one side of the pivot member, said jaws being rotatable with respect to the pivot member. 80

4. In a device of the class described, a long handle, a pivot member extending beyond the end of the handle and positioned to one side of its axis and provided at its outer side with a claw, a pair of jaws at said end of the handle at one side of the pivot member, and means at the opposite end of the handle 85 for drawing said jaws together. 90

5. In a device of the class described, a long handle, a pivot member extending beyond the end of the handle and positioned to one side of its axis and provided at its outer side with a claw, a pair of jaws at said end of the handle at one side of the pivot member, said jaws being rotatable with respect to the pivot member, and means at the opposite ends of the handle for drawing said jaws together and for rotating the same. 100

6. In a device of the class described, a handle, a pair of jaws mounted at one end of the handle and rotatable axially relative thereto, and a pivot member at said end of the handle, said pivot member extending beyond said jaws. 110

7. In a device of the class described, a handle, a pair of jaws mounted at one end of the handle, a pivot member at said end of the handle, said pivot member extending beyond said jaws, and means at the opposite end of the handle for drawing said jaws together. 115

8. In a device of the class described, a handle, a pair of jaws mounted at one end of the handle and rotatable axially relative thereto, a pivot member at said end of the handle, said pivot member extending beyond said jaws, and means at the opposite end of the handle for drawing said jaws together and for rotating the same. 120

9. In a device of the class described, a handle, and a pair of gripping jaws mounted at one end of the handle, said jaws having 130

cutting edges at the sides of the jaws, and a pivot means at said end of the handle beyond said jaws.

10. In a device of the class described, a handle, a pair of gripping jaws mounted at one end of the handle, said jaws having cutting edges at the sides of the jaws, and a cam lever mounted at the opposite end of said handle for forcing said jaws and the cutting edges thereof together.

11. In a device of the class described, a handle, a pair of gripping jaws mounted at one end of the handle, said jaws having cutting edges at the sides of the jaws, and a cam lever mounted at the opposite end of said handle for forcing said jaws and the cutting edges thereof together, said cam lever being rotatable about the axis of the handle for rotating the jaws.

12. In a device of the class described, a handle, a pair of gripping jaws mounted at one end of the handle, said jaws having cutting edges at the sides of the jaws, a cam lever mounted at the opposite end of said handle for forcing said jaws and the cutting edges thereof together, said cam lever being rotatable about the axis of the handle for rotating the jaws, and pivot means at the jaw end of said handle, said pivot means extending beyond said jaws.

In testimony whereof, I have hereunto set my hand at Los Angeles, Calif., this 29 day of April, 1929.

LELAND M. VAN SLYKE.
